UNITED STATES PATENT OFFICE.

ANTHONY F. PAJALIC, OF DETROIT, MICHIGAN.

AIR FILTER.

Application filed March 23, 1925. Serial No. 17,698.

To all whom it may concern:

Be it known that I, ANTHONY F. PAJALIC, a citizen of the United States, residing at Detroit, in the county of Wayne and State 5 of Michigan, have invented certain new and useful Improvements in Air Filters, of which the following is a specification, reference being had therein to the accompanying drawings.

10 This invention relates to an air filter that may be advantageously used at the air intake connection of a carburetor forming part of the fuel supply system of an internal combustion engine, particularly the engines 15 of tractors, trucks, and other motor vehicles.

The primary object of my invention is to provide a simple, durable, and inexpensive device that may be attached to the air intake connection of a carburetor, breather, or 20 any other air supply member for an engine to filter out dirt, dust, and other foreign matter, ordinarily held in suspension by air, and injurious to an engine, by excluding 25 dust and foreign matter, the accumulation of carbon in cylinders and about valves is reduced to a minimum; the scoring of cylinder walls prevented, and a higher degree of efficiency attained in connection with the engine.

30 A further object of this invention is to provide a sheet metal air filter wherein casings and other members are arranged to provide a sinuous, tortuous, or staggered path for air, so that those particles heavier 35 than air will be baffled and caused to leave the device before entering a carburetor or other engine part.

The above and other objects are attained 40 by a mechanical construction that will be hereinafter specifically described and then claimed. Reference will now be had to the drawing wherein Figure 1 is a horizontal longitudinal sectional view of the air filter;

Fig. 2 is a vertical sectional view of the 45 same;

Fig. 3 is a cross sectional view of the air filter taken on the line III—III of Fig. 1; and

Fig. 4 is a similar view taken on the line 50 IV—IV of Fig. 1.

To put my invention into practice, I provide an outer casing composed of a front part 1 and a rear part 2, said casing parts being arranged end to end with the fronting edges thereof bell shaped, as at 3, and spaced apart so as to provide an annular

air inlet opening 4, which also serves as a dirt outlet. The front part of the casing is bell shaped and closed, as at 5, and the rear part 2 of the casing has a large opening 6, into which extends an air outlet conduit, or carburetor connection 7, said connection being centered in the opening 6 by inwardly projecting brackets 8, forming part of the casing rear part 2.

The casing parts, 1 and 2, are formed with annular walls 9, and seated on these walls are the corner portions 10, of a substantially rectangular inner casing 11, said casing having its front end formed with flanges 12, that may be soldered, riveted, or otherwise connected to the front part 1 of the casing. The rear part of the inner casing 11 extends into the rear part 2 of the outer casing and is formed with a wall 13 having an opening 14 in which is fixed the inner end of the conduit, or carburetor connection 7.

In the forward end of the inner casing 11 is a concave-convexo baffle member 15 provided with diametrically opposed arms 16 which extend into the side walls of the inner casing 11, and support the baffle member coaxially of the conduit 7.

Connected to a wall of the inner casing 11 is a hood 18 having its front end abutting a flange 12 of the casing and its rear end open. Attached to the hood 18 and communicating therewith is an air outlet conduit 17, which extends between the outer casing parts, 1 and 2, and is adapted to communicate with a breather, (not shown). The hood 18 will prevent crank case oil or other matter from being drawn into the carburetor connection 7.

Air impinges against the front part 1 of the outer casing and air enters the annular opening 4 where a portion of the air may pass through the rear part 2 of the outer casing and out of the opening 6, carrying with it any dirt or foreign matter. Other quantities of air entering the annular opening 4 may pass between the inner casing 11 and the annular wall 9 of the casing front part 1. From this part of the casing the air passes between the baffle member 15 and the walls of the casing 11, and enters the conduit or carburetor connection 7, and the breather conduit 17. When the air impinges against the baffle member 15, dirt and foreign matter will be deflected downwardly into the front casing part 1 and out of the opening 4.

From the foregoing, it will be noted that the air is filtered as it travels in a tortuous path in the device, and that the outer casing parts are supported through the medium 5 of the inner casing mounted on the conduit or carburetor connection. The breather conduit may also cooperate with the carburetor connection in supporting the device without additional supporting means.

10 It is thought that the utility of my invention will be apparent without further description, and while in the drawing there is illustrated a preferred embodiment of my invention, it is to be understood that the 15 structural elements are susceptible to such variations as are permissible by the appended claims.

What I claim is:—

1. An air filter of the type described comprising a two-part outer casing having a front closed air deflecting end, an inner casing connecting and maintaining the parts of the outer casing spaced apart, a baffle in said inner casing, and an outlet connection coaxially of said casings and fitted in a wall of said inner casing.

2. An air filter as called for in claim 1 wherein said two-part outer casing provides a continuous side air intake opening, and 30 said inner casing affords marginal openings establishing communication between said casings.

3. An air filter comprising an outer cylindrical casing having a side air inlet opening and a front closed end, an air outlet member extending into the rear end of said outer casing, an inner rectangular casing having corner portions connected to said outer casing and a rear wall connected to 40 said air outlet member, and a baffle in said rectangular casing and coaxially of said air outlet connection.

4. An air filter comprising a two-part outer casing closed at its front and having 45 a side opening for the outlet of dirt and the inlet of air, an inner casing extending from

within one part of said casing into the other part thereof and serving as a baffle at the side opening of said outer casing and communicating with a part of said outer casing at the front end of the inner casing to admit air to said inner casing, and an air outlet connection connected to said inner casing.

5. An air filter, as called for in claim 4, 55 and a baffle in said inner casing presenting a convex face to said air outlet connection.

6. An air filter of the type described comprising a two-part outer casing having a front closed end and a side opening adapted 60 to receive air, an inner casing adapted to receive air from the outer casing, an outlet connection for said inner casing, a hood on said inner casing communicating with said outer casing, and an air outlet conduit 65 connected to said hood and extending between the parts of said casing.

7. An air filter comprising a closed front casing part, an open rear casing part, said casing parts cooperating in providing a side air inlet opening, an inner casing closed to the rear casing part and open to the front casing part and adapted to receive air therefrom, said rear casing part affording a passage for air therethrough, and a 70 connection with said inner casing producing an induced current of air supply by withdrawal of air from the air passage of the rear casing part.

8. An air filter comprising an outer casing open at its side and rear only, an inner casing and connection cooperating with said outer casing in providing an air passage through said outer casing, said inner casing having its front end alone establishing communication between said outer casing and said connection so that an induced current in said connection withdraws air from the air passage of said outer casing.

In testimony whereof I affix my signature.

ANTHONY F. PAJALIC.
